UNITED STATES PATENT OFFICE.

GEORGE THEOPHILUS ROHN, OF HERSMAN, ILLINOIS.

CAR-COUPLING.

SPECIFICATION forming part of Letters Patent No. 606,583, dated June 28, 1898.

Application filed January 12, 1898. Serial No. 666,430. (No model.)

To all whom it may concern:

Be it known that I, GEORGE THEOPHILUS ROHN, a citizen of the United States, residing at Hersman, in the county of Brown and State of Illinois, have invented certain new and useful Improvements in Car-Couplers; and I do hereby declare the following to be a full, clear, and exact description of the invention, such as will enable others skilled in the art to which it appertains to make and use the same.

My invention relates to a novel car-coupler, and has for its object the production of a simple and efficient device of this character which will permit cars to be automatically coupled and to be uncoupled by a trainman without the necessity for his exposing himself to danger—as, for instance, by standing between the bumpers, as in the ordinary manner of hand-coupling.

A further object is to provide means whereby when one of the hooks is elevated or released it will cause the elevation and uncoupling of the opposing hook carried by the other car to enable the trainman standing upon one of the cars to simultaneously uncouple the hooks carried by both cars and designed, respectively, to engage the opposing coupler.

To these ends the invention consists in providing what is known as a "twin-hook" coupler, with a laterally-extending yielding arm upon the hook designed to engage the opposing hook and to cause the simultaneous elevation or uncoupling of both hooks when one or the other is actuated for the purpose of uncoupling the cars.

Referring to the drawings, Figure 1 is a side elevation of the contiguous ends of two cars equipped with my device. Fig. 2 is a top plan view of the coupler on a somewhat enlarged scale. Fig. 3 is a similar view showing the parts in the positions they assume when the vehicles are apart. Fig. 4 is a plan view, on a large scale, of one of the hooks, showing the several positions of the hook-elevating arm; and Fig. 5 is an end view of a car equipped with my coupler. Fig. 6 is a vertical section of my coupler.

Referring to the numerals on the drawings, 1 and 2 indicate vehicles—as, for instance, cars designed to be coupled together—provided with the usual draw-heads 3, at the contigu-

ous ends of which are mounted couplers 4 and 5, provided, respectively, adjacent to their opposite sides with recesses 6, in which coupling-hooks 7 are pivoted, and depressions 8, 55 designed, respectively, to receive the pendent noses 9 upon the opposed hooks. The outer faces of the hooks 7 are inclined from the extremity of the hook downwardly to the extremity of the nose 9, and the rear faces 11 60 of the depressions 8 are similarly inclined, but are located a sufficient distance in the rear of the perpendicular front wall of said depressions to permit slight movement of the hook within the coupler when the cars are 65 brought together with some violence, this play of the hook within the coupler preventing its being jostled out of engagement under the somewhat violent shock which usually accompanies the coupling of the cars. The rear or 70 pivoted ends of the coupling-hooks are enlarged somewhat and the forward lower faces 13 of these enlarged ends are inclined and are opposed to a similarly-inclined face 14 at the upper forward corner of the side of the opposing coupler, which contains the depression 75 8 for the reception of the hook.

It will now be seen that when two couplers constructed in accordance with the foregoing description are brought together the inclined 80 faces 10 of the hooks will contact with the opposed inclined faces 14 upon the opposing coupler, and the hooks will ride until the nose 9 has advanced far enough to drop into the depression 8. Opposite movement of the couplers will now bring the opposed perpendicular faces of the hook and recess into engagement and a positive coupling will be effected. In order to effect the uncoupling of the cars, it was originally contemplated to provide elevating devices upon each car which could be actuated to raise the hook out of engagement with the coupler; but it will be observed that such a construction would necessitate the operation of the hook-releasing mechanism carried by both cars, and as this would be practically impossible I have devised simple means for causing either of the hooks when elevated to effect the elevation of the hook upon the opposing coupler. In this manner 100 the trainman standing upon either car can simultaneously effect the coupling or disen-

gagement of the hooks carried by both cars. Each of the hooks is provided at a point adjacent to and slightly above its pintle with an elongated longitudinally-disposed slot 5, 5 in which is terminally pivoted what may be termed a "hook-elevating" arm 16, consisting of the pivoted end 17 and the somewhat elongated end 18 in parallel planes and the intermediate right-angular portion 19. This 10 arm is pivoted within the slot, as indicated at 20, and the end 18 extends laterally from the said face of the hook at a point in advance of the arm 17, a spring 21 being located between one end of the slot and the contiguous 15 face of the end 17 of the arm for the purpose of retaining the latter in its normal position. When the coupling of the cars is effected, the arm 18, carried by each hook, is extended slightly under the opposing hook, which is 20 either provided with a depression for the extremity of the arm or the latter may be located immediately under the portion of the hook in front of the nose. It will now be seen that when one of the hooks is elevated the arm 25 carried thereby will simultaneously elevate the opposite hook until the latter has cleared the coupler. As the cars are now drawn apart should the nose of one hook engage the arm of the opposing hook, if said arms were stationary or fixedly secured, a second coupling 30 would be effected. For this reason I have pivotally mounted these arms and have provided the springs which, while retaining said arms in their proper positions to engage the 35 hooks, will permit of a sufficient yielding of the latter to enable the hooks to be immediately disengaged therefrom as the couplers are drawn apart. It will be seen that the disengagement of the hooks from the yielding 40 arms takes place after said arms have been raised sufficiently to clear the shoulders 14, and while the hooks thus raised will not pull in a direct line upon the yielding arms the movement will be sufficiently approximate thereto to cause the arms to yield for disengaging the hooks in a manner that will be readily understood. Any suitable means 45 for elevating these hooks may be employed; but I prefer to mount a transverse shaft 22 upon each of the cars immediately above the draw-heads and having forwardly-extending levers 23, connected to the hooks, as by flexible pieces 24, and, if desirable, the arms or 50 levers 23 may be also connected to the lower extremities of upwardly-extending connecting-rods 25, provided with handles 26, above the top of the car to permit the trainman to 55 elevate the arms 23, and thereby effect the elevation of the connected hook which auto-

matically effects the elevation of the opposing hook, as we have seen heretofore.

Suitable handles 27 are secured to the opposite ends of the shafts 22 to permit the trainman standing at the side of the car to effect the coupling of the parts in an obvious manner.

Thus I am enabled to produce a simple, durable, and efficient coupling of the class known as "twin hooks," which will be automatically coupled and which may be uncoupled by a trainman standing upon either car or to one side thereof, the usual danger to life and limb being absolutely eliminated; but while the present embodiment of my invention appears to be preferable I do not desire to limit myself to the structural details set out, but reserve the right to change, modify, or vary them at will within the scope of the protection prayed.

Having thus described my invention, what I claim as new, and desire to secure by Letters Patent, is—

1. The combination with a coupling and pivoted hook, of a laterally-extended, spring-actuated pivoted arm carried by the hook, 85 and designed to effect the elevation of the opposing hook, substantially as specified.

2. The combination with a coupler provided with a depression adjacent to one side, and with a pivoted hook adjacent to its opposite 90 side, of an angular laterally-extended arm pivoted within the slot in said hook, and a spring bearing against said arm, substantially as specified.

3. The combination with a coupler provided 95 with a depression adjacent to one side, of a pivoted hook adjacent to the other side of the coupler, an angular laterally-extending hook-elevating arm pivotally mounted in a longitudinal slot in said hook, a spring mounted 100 within the slot and designed to retain the arm in its normal position, a shaft extending laterally across the car, an arm carried by the shaft and operatively connected with the hook, a connecting-rod likewise connected to 105 said hook and extending to the top of the car, and handles upon the connecting-rod and shaft, whereby the hook may be elevated to uncouple the cars and may cause the uncoupling of the opposed hook through the medium 110 of the laterally-extending arm, substantially as specified.

In testimony whereof I affix my signature in presence of two witnesses.

GEORGE THEOPHILUS ROHN.
